THERMOSTATIC SWITCH

Stephen Crum, Minneapolis, Minn., assignor to
 Minneapolis-Honeywell Regulator Company,
 Minneapolis, Minn., a corporation of Delaware

Application October 13, 1939, Serial No. 299,315

21 Claims. (Cl. 200—139)

This invention is directed generally to thermostatic switches, and more particularly to that type of switch which is adapted to respond to the variations in temperature of the surface of a member.

One of the objects of the present invention is to improve the construction of devices of this character so that they may be more easily made and assembled, and so that they may be more easily calibrated and adjusted.

Another object is to mount the thermostat housing outside and on the rear of the main switch casing and to provide it with a pair of mounting arms which are rotatable about said housing through 360 degrees. Thus the device may be vertically mounted on a pipe or other surface regardless of whether it is horizontal, vertical, or any position in between.

Another object is to provide a simple and novel means of adjusting the control setting of the device from outside the casing and to provide a scale on the adjusting arm which can be readily observed.

Still another object of the invention is to have a single resilient member which holds a rotatable carriage for the thermostat and the adjusting arm therefor in operative relation with the casing, and also supplies the frictional force on the adjusting arm to maintain it in its adjusted position. This resilient member relies upon openings in the sides of the casing for holding it in operative position.

These and other objects will readily become apparent as the following specification is read in the light of the accompanying drawing, in which

Figure 1 is a front elevation of the control device with the cover on,

Figure 2 is a side view partially in section, taken along the line 2—2 of Figure 1,

Figure 3 is a section taken along the line 3—3 of Figure 2,

Figure 4 is a detail view of the mounting for one end of the resilient member which holds the parts in assembled relation,

Figure 5 is a plan view of the adjusting arm with an adjustable stop attached, and

Figure 6 is a front elevation of the adjusting arm and stop shown in Figure 5.

Referring now to the drawing it will be seen that the casing 11 which is adapted to be mounted in a vertical position supports the various parts which go to make up the control device of the present invention. Suitably connected to the rear of the casing 11 is a housing 12 gen-

erally circular in outline. This housing may be provided with a series of extensions 13 (Figure 3) which pass through slots in the casing 11 and are bent over as shown to securely connect the housing 12 to the rear of the casing 11. The casing 11 is provided with a hole 14 in which is rotatably mounted the sleeve 15. Secured to the sleeve 15 inside of the housing 12 is a supporting arm 16 which carries at its upper end 17 one end of a coiled bimetallic thermostat 18. The arm 16 seats against a shoulder 19 on the sleeve 15 and is secured to the sleeve by peening over the end of the sleeve.

Seated against an opposite shoulder 21 on the sleeve 15 is a disc 22 which has a circumferential depression 23 adapted to bear against the rear surface of the casing 11. If desired a special bearing member may be placed on the rear of the casing 11 to cooperate with circumferential depression 23 to provide a bearing surface and obtain a more uniform sliding friction as the disc 22 is rotated.

The sleeve 15 is provided with a reduced end 24 which forms a third shoulder against which a centering washer 26 is adapted to seat. An adjusting arm 27 is provided with a hole which receives the washer 26 as the adjusting arm is mounted over the sleeve 15. Mounted over the reduced portion 24 of the sleeve 15 and engaging the washer 26 and a portion of the adjusting arm 27 is a bearing washer 30. The above enumerated parts are held in assembled relation with respect to each other and with respect to the casing 11 by means of a resilient member 32 which is provided with a central hole 33 which receives the reduced portion 24 of the sleeve 15. The resilient member 32 is provided with a reduced end 35 which extends through a hole 31 in the right-hand side of the casing 11 as seen in Figure 3 and a second reduced end 36 which extends through a hole 37 in the other side of the casing 11. Engagement of these ends within the holes 36 and 37 cause the resilient member to bow in the middle and force the disc 22 against the rear of the casing 11 and also to maintain the washers 26 and 30 as well as the adjusting arm 27 in assembled relation with respect to the sleeve 15 and casing 11.

Referring to the detail view in Figure 4 it will be seen that the hole 37 is provided with a widened portion 38 adjacent the rear of the casing 11 and a reduced part 39 which is just wide enough to receive the reduced end 36 of the resilient member 32. The widened portion 38 is provided so that in assembling the device the end

36 including the shoulders 40 may be inserted through the widened portion 38 as the resilient member 32 is moved to the left as seen in Figure 3 to permit the end 35 to be swung downwardly until it can be moved into the hole 36 provided for it in the casing 11. After the end 35 has been put in position to be inserted into the hole 36, the resilient member is moved toward the right at which time the hole 33 receives the reduced end 24 of the sleeve 15 and the end 36 of the member 32 is released to permit it to enter the reduced portion 39 of the hole 37. It will be appreciated that as the holes 31 and 37 are located adjacent the rear of the casing 11 that the resilient member 32 is bent so as to exert a force on the sleeve 15 tending to move it toward the right as seen in Figure 2. This action forces the disc 22 against the casing 11 thereby producing a friction which resists rotation of the disc 22.

The outer end of the bimetallic helix 18 is carried by the end 17 of the arm 16 and the inner end is connected to the actuating rod 42 which extends through the opening in the sleeve 15 and into the casing 11. The inner end of the rod 42 carries a member 43 which is adjustably positioned thereon by means of the screw 44. Member 43 supports the switch clip 45 in which is mounted the mercury switch 46. The wire 47 is used to secure the switch 46 in the proper position in the switch clip 45.

Adjusting arm 27 is provided with arcuate slot 49 through which is passed a screw 50 which enters a tapped hole 51 in an extension 52 on the bearing disc 22. By this arrangement the relative positions of the bearing disc 22 and the adjusting arm 27 may be varied in order to calibrate the control device. The adjusting arm 27 is provided with a horizontal extension 54 and a portion 55 which is spaced from the rear of the casing 11 and which extends downwardly to a point just below the axis of the rod 42. The portion 55 of the arm 27 carries a head 56 which has a kerf 57 which is adapted to receive the blade of a screw-driver. This head 56 is on the axis of the actuating rod 42 about which the adjusting arm 27 is rotated. Therefore if the head 56 is rotated by means of a screw-driver it will not be displaced other than in a rotary sense and the adjusting arm 27 will be rotated about the axis 42.

A cover 60 is adapted to be placed about the casing 11 to completely enclose the mercury switch, the adjusting arm 27 and related parts. The cover 60 is provided with a plurality of indentations 61 which fit into holes 62 in the casing 11 in order to frictionally maintain the cover on the casing 11. The cover 60 is provided with a hole 63 in its face which receives a portion of the head 56 so that a screw driver may be applied thereto for rotating the adjusting arm 27 while the cover is in place. Directly above the hole 63 is a second hole 65 through which a portion of the adjusting arm may be seen. This portion of the arm may be inscribed with a scale 66 for indicating the adjustment of the control device. The hole 65 may have an indicating pointer 67 for cooperation with the scale and a window of transparent material may close this hole if desired.

A mounting device generally indicated at 70 which is provided with a pair of arms 71 and a central opening 72 having sloping sides 73 is mounted over the thermostat housing 12. Each of the arms is provided with a hole 74 by means

of which a strap or similar device may be attached to the arms for mounting the control device on a pipe or other member to whose temperature the thermostat 18 is adapted to respond, so that the rear of the housing 12 is held in heat conducting relationship with the surface of the pipe or member. It will be noted that the housing 12 extends slightly beyond the arms 71 so that as the strap connected to the arm 71 is tightened the housing 12 will be drawn into firmer engagement with the surface of the member on which it is being mounted. It will further be noted that the member 70 may be rotated about the housing 12 through 360° so that the device may be mounted in a vertical position regardless of the angular position of the member 70 so long as this member is in a vertical plane. In other words, the device may be mounted with equal facility on a pipe which extends vertically, horizontally or any position in between. A further feature to be noted is that as the strap is drawn tighter the sloping sides 73 of the member 70 grip the sides and the housing 12 more firmly thereby resisting rotation of the casing 11 with respect to the member 70. Therefore when the control device is once mounted and the strap tightened it will remain in a vertical position.

With the control device mounted as described above the heat from the member to which it is mounted will be conducted through the housing 12 and to the bimetallic element 18. This will cause the element to expand and the coiling and uncoiling of this element due to expansion and contraction will cause a rotation of the actuating rod 42 and hence a rotation of the mercury switch 46 to make and break the circuit therethrough. It will be seen that the bimetallic element 18 is so proportioned with respect to the rod 42 and mercury switch 46 that it will carry these elements entirely by its own resistance so that normally the actuating rod 42 is free of the sleeve 15 and does not rest upon the sides of the hole 43 through this sleeve.

As set forth above in order to adjust the temperature at which the switch 46 will make and break the circuit, the head 56 is rotated by means of a screw-driver causing the arm 27 to rotate about the actuating rod 42 as a center. As the arm 27 rotates it carries with it the disc 22 and sleeve 15 which in turn rotates the outer end of the bimetallic coil 18 thereby varying the position of the mercury switch 46 and hence adjusting the temperature setting of the device. The relative rotation provided between the adjusting arm 27 and the extension 52 of the disc 22 permits the proper calibration of the thermostat 18 with respect to the scale 66. It will be noted that the adjusting arm 27 is provided with two angular extensions 76 and that the rotation of the arm 27 is limited by the engagement of one or the other of these extensions 76 with the resilient member 32.

In some cases it may be desirable to limit the extent to which the device may be adjusted in addition to the limit normally provided by the engagement of one of the extensions 76 with the resilient member 32. In order to provide for this an auxiliary stop member 80 may be mounted concentrically on the head 56 as shown at 81 in Figures 5 and 6. This stop member is provided with a rearwardly extending portion 82 and a generally horizontally extending portion 83 which is provided with a slot 84. The screw 85 extends through a hole in the portion 54 of the adjusting arm 27 and through the slot 84 in the stop mem-

ber 80. A nut 86 is screwed on the end of the screw 85 and is adapted to be tightened against the portion 83 of the stop 80 in order to lock the stop 80 and the adjusting arm 27 in any predetermined position. It will be noted that the horizontally extending portion 83 may extend out beyond the angular extension 16 on the adjusting arm 27 so that as the adjusting arm 27 is rotated in a clockwise direction as viewed in Figures 3 and 6, the extension 83 on the stop member 80 will engage the resilient member 32 thereby limiting the rotation of the arm 27.

The stop member 80 is provided with a shoulder 87 which cooperates with the scale 66 to indicate the temperature to which the adjustment of the arm 27 has been limited. In other words, if it is desired to limit the temperature to which this device may be adjusted to 200° the member 80 is set by means of the screw 85 and nut 86 until the shoulder 87 points to the 200° mark on the scale 66. When this adjustment has been made the extension 83 will engage the resilient member 32 when the device has been set to 200° thereby preventing any further adjustments to a higher temperature.

The usual leveling indicator 90 is provided so that it can readily be determined when the casing 11 has been mounted in the proper vertical position.

As various changes and modifications of this invention may occur to those who are skilled in the art, it is to be understood that I am to be limited only by the scope of the appended claims and not by the specific embodiment disclosed.

I claim as my invention:

1. In a device of the character described, an assembly comprising a switch casing and a thermostat housing mounted on said casing outside thereof, said housing having a surface adapted to be placed against a body to whose temperature the thermostat is to respond, a thermostat in said housing, a switch in said casing actuated by said thermostat, and means for mounting said assembly so that said surface of the housing is held against said body, said means being movable with respect to said assembly so that the assembly may be properly levelled when it is mounted.

2. In a device of the character described, an assembly comprising a switch casing and a thermostat housing mounted on said casing outside thereof, said housing having a surface adapted to be placed against a body to whose temperature the thermostat is to respond, a thermostat in said housing, a switch in said casing actuated by said thermostat, and mounting means rotatably carried by said housing for holding said surface against said body, said rotatable mounting means facilitating levelling of said assembly as it is being mounted.

3. A device of the character described comprising in combination, a casing having an aperture, a sleeve rotatably mounted in said aperture, a coiled bimetallic thermostat outside of said casing and connected at one end to said sleeve, a rod extending through said sleeve and connected to the other end of said thermostat for rotation thereby, a switch within said casing actuated by said rod, a housing for said thermostat attached to and projecting from said casing, and means cooperating with said housing for supporting said device with one surface of said housing against a body to whose temperature the thermostat responds, said means being rotatable with respect

to said housing whereby said device may be levelled as it is mounted.

4. A device of the character described comprising in combination, a casing having an aperture, a sleeve rotatably mounted in said aperture, a coiled bimetallic thermostat outside of said casing and connected at one end to said sleeve, a rod extending through said sleeve and connected to the other end of said thermostat for rotation thereby, a switch within said casing actuated by said rod, a housing for said thermostat attached to and projecting from the back of said casing, means cooperating with said housing for supporting said device with the back surface of said housing against a body to whose temperature the thermostat responds, said means being rotatable with respect to said housing whereby said device may be levelled as it is mounted, an arm for rotating said sleeve and hence adjusting the temperature at which said thermostat will actuate said switch, a scale on said arm, means for rotating said arm, a cover for said casing having aperture means in the front thereof through which a portion of the scale indicative of the adjustment of the thermostat may be seen, and through access may be had to the means for rotating said adjusting arm.

5. A device of the character described comprising in combination, a switch casing, a sleeve extending through an aperture in said casing, a coiled bimetallic thermostat located outside of said casing, one end of said thermostat being positioned by said sleeve, a switch inside of said casing, means controlled by the other end of said thermostat and extending through said sleeve to actuate said switch, an arm for rotating said sleeve and hence adjusting the temperature at which said thermostat will actuate said switch, a scale on said arm, a cover for said casing, said cover having indicating means including an aperture in the front thereof by means of which that portion of the scale indicative of the adjustment of the thermostat may be seen, and means for rotating said arm, said last named means being in substantial alignment with said sleeve, said cover having a second aperture in the front thereof in alignment with said rotating means for access thereto.

6. A device of the character described comprising in combination, a switch casing, a sleeve extending through an aperture in the rear of said casing, a coiled bimetallic thermostat located outside of said casing, one end of said thermostat being positioned by said sleeve, a switch inside of said casing, means controlled by the other end of said thermostat and extending through said sleeve to actuate said switch, an arm for rotating said sleeve and hence adjusting the temperature at which said thermostat will actuate said switch, said arm having a portion extending substantially parallel to the rear of said casing, means on the last named portion of said arm in substantial alignment with said sleeve for rotating said arm and sleeve, a cover for said casing, and a scale on said parallel portion of said arm, said cover having indicating means including an aperture by means of which that portion of the scale indicative of the adjustment of the thermostat is visible, said cover being provided with a second aperture by means of which access may be had to the means for rotating said adjusting arm.

7. A device of the character described comprising in combination, a switch casing, a sleeve extending through an aperture in said casing, a

coiled bimetallic thermostat located outside of said casing, one end of said thermostat being positioned by said sleeve, a switch inside of said casing, means controlled by the other end of said thermostat and extending through said sleeve to actuate said switch, an arm for rotating said sleeve and hence adjusting the temperature at which said thermostat will actuate said switch, indicia for indicating the adjustment thereof, said casing being provided with means for limiting the rotation of said arm, adjustable means for varying the extent to which said limiting means will limit the rotation of said arm, and an indicator cooperable with said adjustable means and said indicia for indicating the limit setting.

8. A device of the character described comprising in combination, a switch casing, a sleeve extending through an aperture in said casing, a coiled bimetallic thermostat located outside of said casing, one end of said thermostat being positioned by said sleeve, a switch inside of said casing, means controlled by the other end of said thermostat and extending through said sleeve to actuate said switch, an arm for rotating said sleeve and hence adjusting the temperature at which said thermostat will actuate said switch, indicia for indicating the adjustment thereof, said casing being provided with means for limiting the rotation of said arm, adjustable means for varying the extent to which said limiting means will limit the rotation of said arm, said last mentioned means being adjustably carried by said adjusting arm, and an indicator cooperable with said adjustable means and said indicia for indicating the limit setting.

9. In a device of the character described, a casing, means rotatably mounted in the rear of said casing, said means having a bearing portion, said casing being provided with a bearing surface cooperating with said bearing portion, resilient means urging said rotatable means in engagement with said bearing surface, the sides of said casing having holes with which the ends of said resilient means engage, thermostatic means connected at one end to said rotatable means, and a control device actuated by the other end of said thermostatic means.

10. In a device of the character described, a switch casing, a sleeve rotatably mounted in the rear of said casing, a bearing surface on said casing, a bearing member carried by said sleeve, an elongated resilient member seated over said sleeve and having reduced ends forming shoulders, said reduced ends extending through apertures in opposite sides of the casing, said shoulders abutting said sides, a thermostat mounted at one end on said sleeve, a rod connected to the other end of said thermostat and extending through said sleeve, and switch means actuated by said rod.

11. In a device of the character described, a switch casing, a sleeve rotatably mounted in the rear of said casing, a bearing surface on said casing, a bearing member carried by said sleeve, an elongated resilient member seated over said sleeve and having reduced ends forming shoulders, said reduced ends extending through apertures in opposite sides of the casing, said shoulders abutting said sides, one of said apertures having a wider portion adapted to receive the shoulders at one end of said resilient member as the other end is being mounted in its aperture, a thermostat mounted at one end on said sleeve, a rod connected to the other end of said

thermostat and extending through said sleeve, and switch means actuated by said rod.

12. In a device of the character described, a switch casing, a sleeve rotatably mounted in the rear of said casing, a bearing surface on said casing, a bearing member carried by said sleeve, an elongated resilient member seated over said sleeve and having reduced ends forming shoulders, said reduced ends extending through apertures in opposite sides of the casing, said shoulders abutting said sides, a thermostat mounted at one end on said sleeve, a rod connected to the other end of said thermostat and extending through said sleeve, switch means actuated by said rod, and means for manually rotating said sleeve whereby the temperature at which the thermostat actuates said switch is varied.

13. In a device of the character described, a switch casing, a sleeve rotatably mounted in the rear of said casing, a bearing surface on said casing, a bearing member carried by said sleeve, an elongated resilient member seated over said sleeve and having reduced ends forming shoulders, said reduced ends extending through apertures in opposite sides of the casing, said shoulders abutting said sides, a thermostat mounted at one end on said sleeve, a rod connected to the other end of said thermostat in a manner to be rotated thereby on temperature changes, said rod extending through said sleeve and within said casing, and a mercury switch mounted on the end of said rod within said casing.

14. In a device of the character described, a switch casing, a sleeve rotatably mounted in the rear of said casing, a bearing surface on said casing, a bearing member carried by said sleeve, an elongated resilient member seated over said sleeve and having reduced ends forming shoulders, said reduced ends extending through apertures in opposite sides of the casing, said shoulders abutting said sides, a thermostat mounted at one end on said sleeve, a rod connected to the other end of said thermostat in a manner to be rotated thereby on temperature changes, said rod extending through said sleeve and within said casing, a mercury switch mounted on the end of said rod within said casing, and means for rotating the sleeve whereby the temperature at which the thermostat actuates the mercury switch is varied.

15. In a device of the character described, control means, a casing therefor, a thermostat for operating said control means supported by said casing so as to project exteriorly thereof, a housing for said thermostat attached to said casing and having a surface adapted to be placed against a body to whose temperature the thermostat responds, said housing being of substantially circular cross-section with an enlarged portion adjacent said surface and a smaller neck portion adjacent said casing, and means for mounting said device comprising a collar loosely fitted on said neck portion so that it may be rotated with respect thereto, and a pair of arms extending laterally from said collar by means of which said surface may be pressed against said body, said pressing action holding said collar against said enlarged portion thereby resisting relative rotation therebetween.

16. In a device of the character described, control means, a casing therefor, a thermostat for operating said control means supported by said casing so as to project exteriorly thereof, a housing for said thermostat attached to said casing and having a surface adapted to be placed against a body to whose temperature the thermostat re-

sponds, said housing being of substantially circular cross-section with an enlarged portion adjacent said surface, a smaller neck portion adjacent said casing and a tapered portion joining said enlarged and neck portions, and means for mounting said device comprising a tapered collar loosely fitted over said neck portion so that it may be rotated with respect thereto, and a pair of arms extending laterally from said collar by means of which said surface may be pressed against said body, said pressing action holding said collar in engagement with said tapered portion, thereby resisting relative rotation there-between.

17. A device of the character described comprising in combination, a switch casing, a sleeve extending through an aperture in said casing, a coiled bimetallic thermostat located outside of said casing, one end of said thermostat being positioned by said sleeve, a switch inside of said casing, means controlled by the other end of said thermostat and extending through said sleeve to actuate said switch, an arm for rotating said sleeve and hence adjusting the temperature at which said thermostat will actuate said switch, a stationary member in said casing for limiting the rotation of said arm, and a member adjustably mounted on said arm for engaging said stationary member, said adjustably mounted member serving to vary the limiting position to which said arm may be moved in one direction.

18. In a device of the character described, a casing, thermostatic means mounted at one side of said casing, a switch, means operatively connecting said switch to said thermostatic means, means for supporting said switch and said connecting means, and an elongated resilient member for holding said supporting means against said side of said casing, said elongated member having a central portion adapted to engage said supporting means and reduced end portions forming shoulders, said reduced ends extending through apertures in opposite sides of said casing laterally disposed from said one side, said shoulders abutting said opposite sides, one of said apertures having a wider portion adapted to receive the shoulder at one end of said member as the other end is being mounted in its aperture.

19. In a device of the character described, a switch casing, a sleeve rotatably mounted in the rear of said casing, a bearing surface on said casing, a bearing member carried by said sleeve, an elongated resilient member seated over said

5 sleeve and having reduced ends forming shoulders, said reduced ends extending through apertures in opposite sides of the casing, said shoulders abutting said sides, a thermostat mounted at one end on said sleeve, a rod connected to the other end of said thermostat and extending through said sleeve, switch means actuated by said rod, an arm for rotating said sleeve whereby the temperature at which said thermostat actuates said switch is varied, and a projection on said arm for engaging said resilient member to limit the rotation of said arm.

20. In a device of the character described, a switch casing, a sleeve rotatably mounted in the rear of said casing, a bearing surface on said casing, a bearing member carried by said sleeve, an elongated resilient member seated over said sleeve and having reduced ends forming shoulders, said reduced ends extending through apertures in opposite sides of the casing, said shoulders abutting said sides, a thermostat mounted at one end on said sleeve, a rod connected to the other end of said thermostat and extending through said sleeve, switch means actuated by said rod, an arm for rotating said sleeve whereby the temperature at which said thermostat actuates said switch is varied, and a member adjustably mounted on said arm for engaging said resilient member to limit the rotation of said arm.

21. A device of the character described comprising in combination, a switch casing, a sleeve extending through an aperture in said casing, a coiled bimetallic thermostat located outside of said casing, one end of said thermostat being positioned by said sleeve, a switch inside of said casing, means controlled by the other end of said thermostat and extending through said sleeve to actuate said switch, an arm for rotating said sleeve and hence adjusting the temperature at which said thermostat will actuate said switch, stop means on said casing for limiting the rotation of said arm, adjustable means on said arm for engaging said stop to vary the limiting position to which said arm may be moved in one direction, and a scale on said arm, said casing having an aperture therein by means of which that portion of the scale indicative of the actuating temperature of the thermostat may be seen, said adjustable means having a portion cooperating with said scale to indicate the limit of said actuating temperature as determined by said adjustable means.

STEPHEN CRUM.
